(57) **CLAIM**

The ornamental design for a package for t-shirts, as shown and described.

DESCRIPTION

FIG. 1 is a top and side perspective view of a package for T-shirts, showing my new design;

FIG. 2 is a rear view thereof;

FIG. 3 is a front view thereof;

FIG. 4 is a top view thereof;

FIG. 5 is a side view thereof;

FIG. 6 is a rear view thereof;

FIG. 7 is a side view thereof;

FIG. 8 is a top view thereof; and,

FIG. 9 is a top view thereof, in a fully opened condition. The broken lines showing is for illustrative purposes only and forms no part of the claimed design.

(57) **CLAIM**

I claim a package for t-shirts, as well as possibly other materials associated with applying graphics to t-shirts such as iron-on transfer paper and the like, as shown in the drawings.

DESCRIPTION

FIG. 1 is a top and side perspective view of a preferred embodiment of the t-shirt package of the present invention; FIG. 2 is a rear view of the package shown in FIG. 1; FIG. 3 is a front view of the package shown in FIG. 1; FIG. 4 is a top view of the package shown in FIG. 3; FIG. 5 is a side view of the package shown in FIG. 3; FIG. 6 is a rear view of the package shown in FIG. 1; FIG. 7 is a side view of the package shown in FIG. 6; FIG. 8 is a top view of the package shown in FIG. 6; FIG. 9 is a top view of the package embodiment shown in FIGS. 1-8, in a fully opened condition; FIG. 10 is a top and side perspective view of an alternative embodiment of the t-shirt package of the present invention; FIG. 11 is a front view of the package embodiment shown in FIG. 10; FIG. 12 is a top and side perspective view of yet another alternative embodiment of the t-shirt package of the present invention; FIG. 13 is a front view of the package embodiment shown in FIG. 12; and, FIG. 14 is a top and side perspective view of the embodiment shown in FIGS. 1-9, with the t-shirt shown in dotted lines and not forming a part of the invention.
